By George A. Rockwell,
atty.

UNITED STATES PATENT OFFICE.

RALPH ABRAHAM SCHOENBERG, OF NEW YORK, N. Y., ASSIGNOR TO IDA S. ROSENHEIM,
OF NEW YORK, N. Y.

MEANS FOR OPERATING SWITCH MECHANISMS.

1,170,347.

Specification of Letters Patent.

Patented Feb. 1, 1916.

Original application filed February 9, 1914, Serial No. 817,472. Patented August 10, 1915, No. 1,149,789.
Divided and this application filed May 21, 1915, Serial No. 29,539.

To all whom it may concern:

Be it known that I, RALPH A. SCHOENBERG, of New York, in the county of New York and State of New York, have invented 5
5 new and useful Means for Operating Switch
Mechanisms, of which the following is a
specification, this application being a division
of my application filed February 9,
1914, Serial No. 817,472.

10 My invention relates to means for operating switch mechanisms and particularly when such mechanisms are placed in sockets, or other receptacles especially when adapted for carrying electric light lamps or
15 attachment plugs.

In the case of sockets or other receptacles it is highly desirable to do away with the unsightliness caused by protruding actuators, such as keys, chains and push-buttons.
20 These actuators are a distinct drawback as a matter of appearance and particularly in the case of very fine fixtures and require not only perforation of the socket or other receptacle but also perforation of the husk
25 or socket cover when the latter is used as well as alinement of the perforations of socket and husk.

One object of my invention is to do away with such protruding actuators and my invention consists partly in providing a support for an electrical appliance such, for example, as a lamp or attachment plug, movable longitudinally in one direction to make the circuit and also movable in the
35 same direction to break the circuit.

A feature consists in a support normally occupying its inner position but movable outwardly in preparation for active operation and then movable inwardly to change
40 the condition of the circuit.

Another feature consists in a step-by-step operating mechanism.

Another feature consists in the mounting of the several parts on relatively movable
45 insulating members.

Other features will be pointed out below.

In the drawings: Figure 1 is a central longitudinal sectional view of a device embodying my invention; Fig. 2 is a section on line 2—2 of Fig. 1; Fig. 3 is a section on line 3—3 of Fig. 1; Fig. 4 is a section on line 4—4 of Fig. 1; Fig. 5 is a detail showing part of the switch mechanism of the device of Fig. 1; and Fig. 6 shows my de-
vice used as a lamp socket and provided 55
with a cord attachment through which the lamp is manipulated to operate the switch.

Reference character 1 indicates the stationary porcelain block, 2 the movable porcelain block, 3 the screw shell, 4 the lining 60
of insulating material inclosing said parts,
5 the metal shell surrounding the lining 4,
6 the cap of shell 5 and 7 and 8 the lead
wires. The stationary porcelain block 1 is
made with a recess 9 within which is ar- 65
ranged a ratchet wheel 10 provided upon
one face with a series of studs 11 coöper-
ating with a spring pawl 12 fastened by a
screw 13 to the movable porcelain block 2.
The porcelain block 2 normally occupies its 70
inner position but is moved outwardly by
hand in preparation for active operation
and is then released and moves inwardly
to make or break the circuit and the spring
pawl 12 moving with it acts to rotate ratchet 75
wheel 10 step by step. The ratchet wheel
10 is made with four laterally projecting
lugs 14 adapted by the rotation of said
wheel to be brought successively into en- 80
gagement with a stationary contact 15 fas-
tened by a screw 16 to the stationary porce-
lain block 1. The contact 15 is made with
a downwardly extending finger 17 which is
in permanent engagement with a contact 85
finger 18 riveted or otherwise secured to the
screw shell 3. A spring detent 19 bears
against ratchet wheel 10 and coöperates
with the studs 11 to prevent reverse move-
ment of said ratchet wheel on the down
strokes of pawl 12. This detent 19 is fas- 90
tened to the stationary porcelain block 2 by
means of a screw 20 which serves also as a
binding post with which the line wire 7 is
connected. Detent 19 not only prevents re-
verse movement of ratchet wheel 10 but also 95
serves as an electric connection between
binding post screw 20 and said ratchet
wheel. The studs 11 are provided and ar-
ranged so that each upward movement of
pawl 12 rotates ratchet wheel 10 a distance 100
equal to the angular distance between two
of the studs so that every other upstroke
of pawl 12 shifts one of the lugs 14 into
engagement with contact 15 while the alter-
nate upstrokes of the pawl 12 disconnect 105
ratchet wheel 10 and contact 15. The cen-
ter contact 21 is made with a threaded hole
to receive the lower threaded extremity of

a post 22 provided at its upper end with a head 23 beneath which is arranged a spring 24, said spring serving to normally hold the block 2 against the porcelain block 1.

On its under side the porcelain block 1 is made with a recess 25 within which is arranged a contact 26 that is fastened to the porcelain block 1 by means of a screw 27. The screw 27 serves as a binding post to which the other line wire 8 is connected, and the contact 26 is in permanent engagement with a stationary contact 28 provided on the center contact 21. The screw shell 3 and porcelain block 2 are moved bodily to open and close the circuit at 19-15 and when thus moved the contacts 28 and 18 slide upon the contacts 17 and 25 without leaving the latter. In Fig. 1 I have shown a connecting plug 29 mounted within the screw shell 3 and at 30 and 31 are the line wires leading from this connecting plug to the heater or other instrument. When the circuit through the heater or other instrument connected with the wires 30 and 31 is open and it is desired to close the same the operator may accomplish this merely by pulling upon said wires and then releasing them. The pull upon the wires draws the connecting plug 29, screw shell 3, porcelain block 2 and post 22 outwardly against the pressure of spring 24 which latter returns said parts to their innermost positions when the pull upon wires 30 and 31 is relaxed. Pawl 12 moves with the porcelain block 2 and through its engagement with the ratchet wheel 10 turns the latter one step carrying one of the lugs 14 into engagement with the contact 15 thereby closing the circuit through the heater or other instrument. When it is desired to open the circuit through the heater or other instrument the operator will again pull upon the wires 30 and 31 which results in another in and out movement of the connecting plug 29 and parts connected therewith. When block 2 is thus moved with the connecting plug 29 its pawl 12 again moves ratchet wheel 10 one step carrying the lug 14 resting against contact 15 away from and out of engagement with the latter thus opening the circuit through the heater or other instrument. It will thus be seen that with this form of my invention an important advantage resides in the construction which permits of its being operated from a distant point to open and close the circuit through the medium of the wires 30 and 31.

My improved switch device may be used to hold a lamp as shown in Fig. 6 and if it is to be placed in an elevated position where it cannot be conveniently reached I may provide an attachment 32 shown in Fig. 6 consisting of an annular flexible strap 33 whose ends are fastened together by means of a screw 34 so that the strap is confined between two shoulders 35 and 36 that are pro-

vided upon the exterior of shell 5. This strap 33 is made with a depending arm 37 extending downwardly alongside of the lamp bulb 38 and at the lower end of this arm there is provided a bell-shaped cord 70 guiding aperture 39. One end of a cord 40 is tied around the shank of the bulb 38 and said cord extends therefrom downwardly through the guide 39 with its lower end arranged in a convenient position.

The stationary porcelain block 1 of Fig. 1 is made at its lower end with two diametrically opposite lugs 41 occupying two notches 42 provided in the movable porcelain block 2. These lugs and sockets connect the two porcelain blocks so that they can be moved relatively toward and from each other but are held against relative rotative movement.

What I claim is:

1. A device of the character described comprising switch mechanism including an immovable contact and a contact movable into and out of engagement with said immovable contact; a support normally occupying its inner position but movable outwardly in preparation for operative movement and movable inwardly to change the condition of the circuit through said switch mechanism; and an electrical appliance carried by the support and having a terminal in circuit with said switch mechanism.

2. A device of the character described comprising switch mechanism including an immovable contact and a contact movable into and out of engagement with said immovable contact; a support normally occupying its inner position but movable outwardly in preparation for operative movement and movable inwardly both to make and break the circuit through said switch mechanism; and an electrical appliance carried by the support and having a terminal in circuit with said switch mechanism.

3. A device of the character described comprising switch mechanism including a fixed contact and a rotatable contact to engage said fixed contact; a support normally occupying its inner position but movable outwardly in preparation for operative movement and movable inwardly to change the condition of the circuit through said switch mechanism; and an electrical appliance carried by the support and having a terminal in circuit with said switch mechanism.

4. A device of the character described comprising a body comprising two blocks of insulating material connected together with provision for limited relative movement toward and from each other, a pair of terminals on one of said blocks for connection with the lead wires of a circuit; a spring yieldingly tending to move said blocks toward each other; a screw shell and center 125

- contact mounted on the other block; means electrically connecting said shell and center contact with said terminals, said means including a switch comprising a rotatable member and means through which relative movement of said blocks toward each other shifts said rotatable member one step to reverse the condition of the circuit.
5. A device of the character described comprising two blocks of insulating material connected together with provisions for limited relative movement toward and from each other; a spring for urging said blocks toward each other; a screw shell, a center contact and a switch actuating pawl carried by one of said blocks; and a circuit-controlling switch carried by the other block, comprising a rotatable switch member that is actuated by said pawl when the blocks are moved relatively toward and from each other.
6. A device of the character described comprising two blocks of insulating material connected together with provision for limited relative movement toward and from each other; a spring for moving said blocks relatively toward each other; a screw shell and center contact carried by one of said blocks; a circuit controlling switch on the other block comprising a rotatable switch member; and an actuator for said rotatable

member operated by relative movement of said blocks.

7. In a device of the character described the combination of a socket; switch mechanism mounted on said socket; a support movable longitudinally to operate the switch mechanism; a guide connected to the socket; and a member passing through said guide to move the support.

8. A device of the character described comprising switch mechanism including an immovable contact and a contact movable into and out of engagement with said immovable contact; a support movable outwardly to break the circuit through said switch mechanism; and an electrical appliance carried by the support and having a terminal in circuit with said switch mechanism.

9. A device of the character described comprising switch mechanism including an immovable contact and a contact movable into and out of engagement with said immovable contact; a support movable outwardly both to make and break the circuit through said switch mechanism; and an electrical appliance carried by the support and having a terminal in circuit with said switch mechanism.
